UNITED STATES PATENT OFFICE.

WILLIAM EDWIN PAYNE AND WALFRID S. EKLUND, OF DONNER, LOUISIANA.

AUTOMATIC FIRE-ESCAPE.

1,136,436.

Specification of Letters Patent.

Patented Apr. 20, 1915.

Application filed December 27, 1913. Serial No. 809,014.

To all whom it may concern:

Be it known that we, WILLIAM E. PAYNE, a citizen of the United States, and WALFRID S. EKLUND, a subject of the Emperor of 5 Russia, residing at Donner, in the parish of Terrebonne and State of Louisiana, have invented certain new and useful Improvements in Automatic Fire-Escapes; and we do hereby declare the following to be a full, clear, 10 and exact description of the invention, such as will enable others skilled in the art to which it appertains to make and use the same.

This invention relates to the type of fire- 15 escapes comprising a reel having automatic means for governing its unwinding and rewinding it.

This invention further aims to improve devices of the above mentioned character so 20 as to render them more practical, durable, reliable and efficient in operation, cheaper to manufacture and more commercially desirable.

The above and additional objects are accomplished by such means as are illustrated 25 in the accompanying drawings, described in the following specification and then more particularly pointed out in the claims which are appended hereto and form a part of this 30 application.

With reference to the drawings, wherein 35 we have illustrated the preferred embodiment of our invention as it is reduced to practice, and throughout the several views of which, similar reference numerals designate corresponding parts, Figure 1 is a front elevation illustrating the device in assembled position, Fig. 2 is a bottom plan view, Fig. 3 is a side elevation, Fig. 4 is a detail view of 40 the governing means illustrating it partly in section, Fig. 5 is a detail side elevation of the governing means showing the central portion thereof in section, Fig. 6 is a detail sectional view taken on line 6—6 of Fig. 1 illustrating the rope guiding means, Fig. 7 is a detail elevation of the rope guide means, Fig. 8 is a cross sectional view illustrating 45 the detail construction and arrangement of the rope guiding means, and Fig. 9 is a detail transverse sectional view taken on line 9—9 of Fig. 1 illustrating the spring means for rewinding the cable upon the drum.

Referring to the drawings forming a part 50 of this specification and in which like numerals are employed to designate correspond-

ing parts, the numeral 1 designates as an entirety a preferably rectangular skeleton frame work upon which the operating mechanism forming a part of the invention is mounted after a manner which will be later 60 more fully described. Rotatably journaled in bearing standards 2 and 3 that are carried upon the ends of the frame 1 is a winding drum 4 provided with the usual end flanges 5 and formed of the usual cylindrical shape. 65 This winding drum 4 is rotatably mounted upon a fixed shaft 6 secured at its terminals in the bearing standards 2 and 3. Wound upon the drum 4 is a suitable rope or cable 7 secured at one terminal in any suitable 70 manner to the drum and provided with a loop 8 at its other terminal that is adapted to hang below the drum and be grasped by persons or a person seeking escape from a burning building by descending to the 75 ground.

The main frame 1 is provided at suitable places with bolt openings 9 by means of which the device may be secured to the wall of a building at a convenient point near a 80 window preferably above the window frame upon the outside or inside of the building wall so that the end 8 of the cable 7 is in a position where it may be readily grasped for operation.

The winding drum 4 is provided with a longitudinal end opening aperture 10 in which is mounted a plurality of flat coil springs 11. Suitable cylindrical casings may be provided for the springs and the 90 terminals of the springs are secured as at 12 to the inner face of the winding drum 4 and to a collar 13 fixed upon the fixed shaft 6, respectively, as will be clearly seen with reference to Fig. 9 in the drawings. These 95 springs 11 are arranged to wind up when a person or persons is making a descent that is, when the cable 7 is unwinding from the drum 4, and are further adapted to rewind the cable 7 upon the drum 4 automatically, 100 upon the release of the weights upon the cable 7.

It has been found necessary to provide some means for rewinding the cable 7 upon the drum 4 in even layers, and in this connection there has been provided upon the lower terminal of the frame 1 an approximately U-shaped supporting arch or like structure 14. Mounted upon opposite sides of this U-shaped supporting bracket are 110

guide bars 15 and 16 that are bolted or otherwise suitably secured to the arms of the U-shaped supporting member and are each provided with a plurality of laterally extending spaced rack pins 17. These guide bars 15 and 16 extend longitudinally of the frame 1 and are also provided with longitudinal spaced slots 18 for a purpose which will be later more fully disclosed.

10 Mounted and adapted for operation between the guide bars 15 and 16 is a guide pulley designated as an entirety by the numeral 19. This guide pulley 19 is loosely and rotatably mounted upon a pin or shaft 20, the ends of which have bushings thereon that are adapted for bearing engagement with the slot 18 in the opposed faces of the guide bars 15 and 16 as will be clearly seen with reference to Fig. 3 in the drawings.

15 Keyed upon the shaft 20 upon opposite sides of the pulley 19 are small gear wheels 21 and 22 that are each adapted for engagement with the rack pins 17 as will be clearly seen with reference to Figs. 1 and 3 in the drawings.

20 These small gears 21 and 22 are spaced from the extreme ends of the shaft 20 to facilitate the mounting of the ends of the shaft within the slots 18 in the guide bars 15 and 16 to permit free sliding movement of the shaft longitudinally of the frame after a manner which will be later more fully described.

25 Loosely mounted upon the shaft 20 between the gear 21 and guide pulley 19 is an angular supporting bracket 23 that is provided centrally with a longitudinal slot 24 to facilitate its loose mounting upon the shaft 20 and for a purpose which will be later more fully described. The ends of this member 23 are offset to provide bearings 24' upon one side of which are journaled rollers 25 and 26. These rollers 25 and 26 are adapted to engage the upper and lower edges of the outermost guide bar 15 as will be clearly seen with reference to Fig. 3 to facilitate the free sliding movement of the rope guiding means.

30 The pulley 19 is provided with a circular recess opening upon its inner face and designated 27, and that is adapted to be closed when the device is in assembled position by means of a removable circular closure plate 28 that is held in engagement by suitable screws or like securing means. Keyed upon the shaft 20 and disposed adjacent one side of the recess 27 in the pulley 19 is a small gear wheel or pinion 29 which meshes with a larger gear wheel or pinion 30 that is rotatably mounted upon a journal pin 31 which is secured within the recess 27 to one side of the center thereof. This gear wheel 30 is adapted to rotate relative to the pulley 19 as will be clearly seen with reference to Fig. 8 in the drawings. Loosely mounted

35 upon the shaft 20 and disposed adjacent the

40 gear 29 is a gear wheel 32 that is similar in size to the gear wheel 29 and provided upon one side with an integral securing collar or hub 33. This collar 33 is adapted to extend through the slot 24 in the bracket 23 and to be suitably secured therein so that its outer end is flush with the outer surface of the central portion of the bracket 23. It will thus be seen that the gear 32 is fixed while the pulley 19, shaft 20, gears 21, 22 and 29 thereon and the gear wheel 30 are free to rotate. The gears 29 and 32 are equal in size when taken together to the gear 30 and mesh therewith as will be clearly seen with reference to Fig. 8 in the drawings.

45 In operation the cable 7 is wound once around the guide pulley 19 and the loop end 8 is disposed below the pulley as hereinbefore described. When a weight is placed upon the cable 7, that is, when a descent is to be made and assuming the pulley 19 to be at one end of the guide bars 15 and 16, the rotation of the pulley wheel caused by the downward movement of the cable moves the gear wheel 30 around the shaft 20 and gears 29 and 32 thereon. As the gear 30 is moved arcuately relative to the gears 32 and 29, the gear 32 which is fixed causes the rotation of the gear 30 and a subsequent movement of the gear 29, which, in being keyed upon the shaft 20 causes the same to rotate, thus the gears 21 and 22 move the pulley back and forth on the guide bars 15 and 16 by engaging the rack pins 17 as will be clearly seen with reference to Fig. 1 in the drawings.

50 It will be apparent that the positive guiding of the cable is provided by the action of the guiding means hereinbefore described thus providing an even winding and unwinding of the cable upon the drum 4 and preventing possible injury to persons in making a descent by jerking which would occur should the cable be tangled or wound unevenly.

55 We have provided means designated 34 as an entirety for regulating the speed of the rotation of the drum when the cable is being unwound thereon and means designated 35 as an entirety which will regulate the speed of rotation of the drum when the cable is being unwound therefrom. An extension bearing standard 36 is secured adjacent one end of the frame 1 in any suitable manner and is provided with divergent bearing arms 37 and 38. Journaled in the bearings 37 and 39 formed integral with the bearing member 3 and frame 1 is a shaft 40 that is extended through the bearing 39 and provided upon its extended terminal with a pinion 41 that is keyed upon the shaft and adapted to mesh with a large gear wheel 42 fixed upon the adjacent head of the drum 4. A large gear wheel 43 similar to the one designated 42 is loosely mounted upon the

60 110

65 115

70 120

75 125

80 130

shaft 40 so that it is interposed between the governing mechanism 34 that is mounted upon the shaft 40 and the bearing 39. This gear wheel 43 is adapted to mesh with a small pinion 44 that is keyed upon a shaft 45 which is journaled in the bearing 38. The governing mechanism 35 is operatively connected with or mounted upon the shaft 45 and is operated through the medium of 10 the gears 41, 42, 43 and 44 after a manner which will be later more fully disclosed.

The governing mechanism 34 consists of a circular disk 46 that is of a slightly less diameter than the gear wheel 43 and is 15 adapted to bear against the outer face of the gear 43 and is further loosely mounted upon the shaft 40. This disk 46 is provided with a hub 47 in which is formed an angular slot or groove 48 that is adapted to receive a pin 49 fixed upon the shaft 40. The arrangement of the pin 49 and slot 48 is to cause the rotation of the gear 43 upon the unwinding of the drum 4 and to hold the gear 43 against rotation when the cable is 20 rewinding, consequently preventing operation of governor 35 as will be clearly seen with reference to Figs. 1 and 2 in the drawings. A helical spring 50 is mounted upon the shaft 40 and held in position thereon by 25 means of a transverse securing pin 51, adapted to engage the hub 47 and aid the pin and slot arrangement in forcing the disk 46 into engagement with the adjacent face of the gear 43 to cause the same to 30 rotate by frictional engagement of the disk with the gear as will be clearly seen with reference to Fig. 1 upon the unwinding of the cable, when the gear 43 in rotating operates the governor 35. A plurality of 35 hingedly secured and preferably square vanes 52 are hingedly secured upon the outer face of the disk 46 and are held in close and approximate parallel relation to the disk by means of flat leaf springs 53 that are secured 40 at one terminal to the disk and bear at their other terminals upon the outer faces of the vanes 52. The vanes 52 are forced outwardly in angular relation to the disk 46 during the rotation of the disk 46 when 45 the drum 4 is rewinding and thus, to some extent governs the movement of the drum 4.

The governing mechanism 35 that is mounted upon the shaft 45 consists of a pair of elongated plates 54 and 55 that are 50 mounted upon the shaft 45 and disposed at right angles thereto upon opposite sides in diametrically opposed relation to each other. Each of the plates 54 and 55 are provided with inwardly opening longitudinal end 55 slots 56 for a purpose which will be later more fully disclosed. A cylindrical sleeve or tube 57 is mounted transversely through the shaft 45 so that the tube extends an equal distance upon each side of the center beyond the shaft at right angles thereto. A

rod 58 is secured at one terminal to each of the members 54 and 55 at a point centrally of the upper ends thereof and extends downwardly, between the sides of the slots 56. Each of these rods 58 are adapted to be slidably mounted within the tube 57 to permit the sliding of the plates 54 and 55 outwardly and angularly with relation to the shaft 45 to provide the desired governing action. 70

A pair of coil springs 59 and 60 is mounted between the inner ends of the plates 54 and 55 and serve to return the plates to their normal positions after being moved outwardly and turned by the centrifugal action during the rotation of the shaft 45. The 75 springs 59 and 60 are provided with hook terminals 61 adapted for engagement with hook members 62 carried upon the inner edges of the plates 54 and 55. 80

The springs 59 and 60 are arranged upon opposite sides of the shaft 45 and in being provided with the hook terminals 61 are readily detachable to provide for substitution of weaker or stronger springs as desired. The members 54 and 55 are connected with 90 the tube 57 by means of connecting arms 63 and 64 that are provided with socket heads 65 adapted to receive extended ball members 66 secured adjacent the ends of the tube 57 upon one side thereof, and similar ball members 67 that are secured upon opposite sides of the center line of the plates 54 and 55 thus providing ball and socket connection for the arms 63 and 64. These arms 63 and 64 serve to turn the members 95 54 and 55 angularly with relation to the shaft 45 and are arranged angularly with relation to the vertical axis of the tube 57, when the members 54 and 55 are in normal position. It will be apparent that upon the 100 rotation of the shaft 45 that the centrifugal force will cause the members 54 and 55 to be turned angularly with respect to the tube 57 upon the action of the springs 59 and 60, thus governing the speed of the rotation of 105 the drum 4 when said drum is unwinding. 110

When the cable is rewinding on the drum the pin 49 and slot 48 in the governor 34 causes the disk 46 to move out of engagement with the gear 43, thus the gear 43 is 115 not rotated and the governor 35 is not operated.

It has been found desirable to removably secure one of the heads of the drum 4 to facilitate the proper positioning of the 120 mechanism within the drum for automatically rewinding it upon the release of weight upon the cable 7. The general construction of the frame 1 is of an integral formation of some suitable material such as angle 125 iron or the like that is provided with great strength and powers of durability. It has been found desirable in some instances to provide a hood or casing for the machine to protect the same against the elements and in 130

this connection it is not thought necessary to illustrate a casing or cover or describe the same in detail.

It is apparent with reference to the foregoing description and accompanying drawings that there has been provided a fire escape which will permit the expeditious and safe descent of a person or persons desirous of escaping from a burning building, to the ground and immediately upon the release of the weight upon the cable, the automatic rewinding in an even and reliable manner is provided. It is desirous of emphasizing the fact that the speed of the rotation of the drum 4 is governed by the governing means hereinbefore described to such an extent as to permit the safe descent of persons or a person desirous escaping from a burning building.

20 In reduction to practice, we have found that the form of our invention, illustrated in the drawings and referred to in the above description, as the preferred embodiment is the most efficient and practical; yet realizing that the conditions concurrent with the adoption of our device will necessarily vary, we desire to emphasize the fact that various minor changes in details of construction, proportion and arrangement of parts 25 may be resorted to, when required, without sacrificing any of the advantages of our invention, as defined in the appended claims.

What is claimed is:—

1. An automatic fire escape, comprising a 35 supporting frame, a winding drum journaled in the frame and adapted to have a cable wound thereon and means for governing the speed of rotation of said winding drum when the drum is rewinding comprising a shaft rotatably journaled in the frame, means for operatively connecting the shaft

with the winding drum to cause rotation of said shaft, a gear wheel loosely mounted upon the shaft, a disk loosely mounted upon the shaft and adapted to engage one side 45 face of the gear wheel, means for rotating the disk when the drum is unwinding and rewinding, a spring mounted upon the shaft and adapted to force the disk into frictional engagement with the loosely mounted gear 50 wheel to cause the same to rotate when the cable is unwinding, a plurality of hingedly secured vanes carried on said disk, means for yieldingly holding the vanes in close and approximately parallel relation to the 55 disk, said vanes adapted to be moved outwardly in angular relation to the disk by atmosphere resistance during the rotation of the disk in the opposite direction during the rewinding of the cable, a second shaft, 60 means for operatively connecting the second shaft with the loosely mounted gear on the first shaft, and governing means on the second shaft operated by centrifugal force during the rotation thereof, when the cable 65 is unwinding.

2. In an automatic fire escape a rotatable drum to have a cable wound thereon, means for governing the speed of the rotation of said drum when the drum is rewinding, 70 means for governing the speed of rotation of the drum when said drum is unwinding and means for preventing operation of said first named governing means upon the operation of said last named governing means. 75

In testimony whereof we affix our signatures in presence of two witnesses.

WILLIAM EDWIN PAYNE.
WALFRID S. EKLUND.
